CLAIM

The original design for a multi-purpose light, as shown and described.

DESCRIPTION

FIG. 1 is a front side perspective view of a multi-purpose light;

FIG. 2 is a right side view of the multi-purpose light;

FIG. 3 is a left side view of the multi-purpose light;

FIG. 4 is a front elevation view of the multi-purpose light;

FIG. 5 is a rear elevation view of the multi-purpose light;

FIG. 6 is a top plan view of the multi-purpose light; and,

FIG. 7 is a bottom plan view of the multi-purpose light.

The dashed or dotted lines form no part of the claimed design.

Portions of the claimed design are shown in dash-dot-dash broken lines to indicate indeterminate length.
